UNITED STATES PATENT OFFICE.

HENRY W. HISS, OF WYOMING, NEW JERSEY, ASSIGNOR TO TIDE WATER OIL COMPANY, OF BAYONNE, NEW JERSEY, A CORPORATION OF NEW JERSEY.

DESIGN FOR AN ADVERTISING DEVICE OR SIMILAR ARTICLE.

Application filed October 27, 1921. Serial No. 510,974. Term of patent 14 years.

To all whom it may concern:

Be it known that I, HENRY W. Hiss, a citizen of the United States, residing at No. 136 Prospect Avenue, Wyoming, in the county of Essex, State of New Jersey, have invented a new, original, and ornamental Design for an Advertising Device or Similar Article, of which the following is a specification, reference being made to the accompanying drawing, forming part hereof.

I claim:

The ornamental design for an advertising device or similar article as shown.

HENRY W. HISS.
